UNITED STATES PATENT OFFICE.

CARL B. HERZINGER, OF PORTLAND, OREGON.

GRAVITY-CARRIER.

1,149,763.

Specification of Letters Patent. Patented Aug. 10, 1915.

Application filed October 3, 1914. Serial No. 864,715.

To all whom it may concern:

Be it known that I, CARL B. HERZINGER, a citizen of the United States, residing in the city of Portland, county of Multnomah, 5 and State of Oregon, have invented certain new and useful Improvements in Gravity-Carriers, of which the following is a specification.

My invention relates to gravity carriers, 10 and more particularly to means for automatically controlling the speed of a gravity carrier of the type adapted to run upon a suspended cable, mono-rail, or the like.

The invention is particularly adapted to 15 make possible a more general use of carriers of this character for transporting ore, lumber, logs, and the like from an elevation or place where there is sufficient grade to cause the carrier to run by gravity. Such carrier 20 systems can be installed in places where it is next to impossible and most expensive to build a railroad. By providing means as a part of a carrier for automatically regulating the speed thereof, under gravity, it is 25 possible to apply the carriers to the trackways, attach the loads thereto, and set them off alone without danger of their attaining a speed which would do damage.

In order that others may thoroughly understand my invention, I have shown one 30 practical embodiment thereof adapted for use on a cable which is, of course, the easiest trackway to be arranged across rough and hilly country. In the embodiment of the 35 invention used for purposes of illustration, I have shown two different kinds of controlling or retarding devices for the carrier, each of which is actuated by a wheel of the carrier, and each of which acts upon said 40 wheel for the purpose of retarding it, or holding it against too great a speed. Each of said devices is opposed by the air in its movements and an increased speed increases that opposition.

45 In the drawings, Figure 1 is a front, or edge, view of a cable carrier with one form of retarding device applied thereto; Fig. 2 is a side elevation of the same; Fig. 3 is an edge view of a cable carrier with another 50 form of retarding device applied thereto; and Fig. 4 is a side elevation of the same, showing a load carried.

Referring to Figs. 1 and 2 of the drawings, the carrier here shown comprises a 55 body 1, which may be of any suitable form and material, with two wheels, 2 and 3,

adapted to run upon a supporting cable 4. A carrier hook or member 5 is pivotally connected to said body, as at 5', preferably closer to the front wheel 2, as indicated, 60 upon which the retarding device, herein-after referred to, operates. In this embodiment of the invention, I have shown a fan or vane 6, attached directly to the axle of the front wheel 2 so as to turn therewith 65 and to be operated thereby. Said vane is mounted at one side of the device so as not to interfere with any supporting devices for the cable 4 on the opposite side of the device. Thus as the device runs down grade 70 the vane 6 is operated so as to beat the air with the result that the front wheel 2 is retarded according to the speed at which the device is running.

In Figs. 3 and 4, instead of using a vane, 75 I have provided a cylinder A, pivotally secured to the side of the body 1, substantially as indicated at A', with a piston and piston rod B, connected by means of a crank C with the axle of the front wheel 2, as indicated. The cylinder is provided at its opposite ends with cocks, A²—A² whereby to regulate the passage of the air to and from the cylinder as the piston is operated therein by the crank of the wheel 2. 80

Thus again I have provided a retarding or controlling means actuated by a wheel of the carrier on which it is placed and operating on said wheel to retard the speed of said device. It is also a device whose movement is opposed by the air, though any fluid might be used with this form of the invention for retarding the movement of the piston. 85

I am aware that changes can be made in 90 the embodiments of the invention here shown for illustrative purposes without departing from the spirit thereof, and I do not, therefore, limit the invention except as I may be limited by the hereto appended 100 claims.

I claim,—

1. A gravity carrier of the character referred to comprising in combination with a track-way, a carrier device having one or 105 more wheels adapted to said track-way and adapted to run by gravity only, and a retarding device operatively connected therewith and controlled by the speed thereof for checking the speed of said gravity carrier. 110

2. A device of the character referred to comprising in combination with a support-

ing cable, a body provided with one or more wheels adapted to run on said cable, operable by gravity solely and without other power-propelling means, and means operated by the movement of said device for controlling its speed.

3. A gravity carrier of the character referred to comprising in combination with a supporting cable, a body having one or more 10 wheels adapted to said cable, a supporting member pivotally connected to said body, and a retarding device connected with and operated by the axle of one of said wheels to check the speed of said device, substantially as described.

4. A gravity carrier system comprising an aerial cable, a carrier car adapted to run solely by gravity thereon, without other propelling means, means for supporting a load 20 on said carrier car, and means for automatically checking the speed of said car on said cable.

5. A gravity carrier of the character referred to comprising a body without power 25 mechanism, one or more wheels mounted therein and projecting below the same and adapted for a gravity trackway, an elevated gravity trackway, a supporting arm projecting downwardly from said body below 30 said trackway, and means constituting a part of said carrier and operable by the movement thereof to retard the speed of said gravity carrier.

6. In combination with a gravity carrier 35 adapted to be operated solely by gravity, a fan or vane adapted to be driven by said carrier in its movement, whereby it operates as a retarding means to said carrier.

7. In combination with a gravity carrier 40 having one or more carrier wheels, of a fan or vane connected with and driven by

the axle of one of said wheels, whereby it operates to retard said carrier.

8. A gravity carrier of the character referred to comprising in combination with a 45 supporting cable, a body having one or more wheels adapted to said cable, a carrier arm projecting downwardly from said body below said cable, and a retarding member connected with and operated by the axle of one 50 of said wheels, substantially as described.

9. A gravity carrier of the character referred to comprising in combination with a supporting cable, a body having one or more carrier wheels adapted to said cable, 55 a depending load-supporting part, and a revolving retarding device connected with and driven by the axle of one of said carrier wheels.

10. In combination with a cable, a carrier 60 adapted to run by gravity thereon comprising a body having one or more carrier wheels adapted to said cable, a load-supporting arm depending from said body at one side of 65 said cable, and a retarding device comprising a fan connected to and driven by the axle of one of said carrier wheels, whereby it operates under speed to retard the movement of said carrier, substantially as described.

11. In combination with a carrier wheel 70 of a gravity carrier, a fan connected coaxially with said wheel at one side thereof and revolved therewith, for the purpose referred to.

Signed at Portland, Multnomah county, Oregon, this 28th day of September, 1914.

CARL B. HERZINGER.

In presence of—

THEODORE G. A. BOER,
CLYDE EVANS.
